UNITED STATES PATENT OFFICE

WILLIAM B. MILES, OF DOWNERS GROVE, ILLINOIS

DESIGN FOR A CHILD'S VEHICLE

Application filed August 13, 1930. Serial No. 36,659. Term of patent 3½ years.

To all whom it may concern:

Be it known that I, WILLIAM B. MILES, a citizen of the United States, residing at Downers Grove, in the county of Du Page and State of Illinois, have invented a new, original, and ornamental Design for Child's Vehicle, of which the following is a specification, reference being had to the accompanying drawing, forming part hereof, wherein—

Figures 1 and 2 are, respectively, a side elevation and a plan view of a child's vehicle showing my new design.

I claim:

The ornamental design for a child's vehicle, as shown.

WILLIAM B. MILES.
